UNITED STATES PATENT OFFICE.

LESLIE SYDNEY POPE, OF RAYMOND, WASHINGTON.

GIN-CLEANER.

1,390,638.

Specification of Letters Patent. Patented Sept. 13, 1921.

Application filed November 5, 1920. Serial No. 421,907.

To all whom it may concern:

Be it known that I, LESLIE SYDNEY POPE, a citizen of the United States, residing at Raymond, in the county of Pacific, State of Washington, have invented a new and useful Gin-Cleaner; and I do hereby declare the following to be a full, clear, and exact description of the invention, such as will enable others skilled in the art to which it appertains to make and use the same.

The invention relates to gin cleaners and has for its object to provide a device of this character comprising a bar extending through the gin and disposed below the gin saws and provided with curved fingers which extend upwardly and are disposed between the gin ribs, said bar having its ends provided with rectangular shaped portions slidably mounted in segmentally shaped slots in the sides of the gin frame for guiding said bar and preventing the same from rotating during its upward movement.

A further object is to provide the ends of the cleaner bar with a reduced cylindrical portion adapted to be received by bifurcated ends of rockable levers pivoted to the sides of the gin frame, the other ends of said levers having pivotally connected thereto rods which rods are in turn pivotally connected to the pivoted front of the gin casing, when said casing is pivoted upwardly, the cleaner bar will be moved upwardly to operative position for cleaning the saw teeth which may become clogged and gummed.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:—

Figure 1 is a side elevation of a gin showing the cleaner operating mechanism applied thereto.

Fig. 2 is a view similar to Fig. 1 with a side broken away to show the interior structure and the cleaner bar operating mechanism on the opposite side of the gin.

Fig. 3 is a top plan view of the cleaner bar.

Fig. 4 is a rear view of the gin, the rear

wall being broken away to show the cleaner bar within the gin.

Fig. 5 is a perspective view of the operating lever at one end of the gin showing a portion of the cleaner bar in the bifurcated end thereof.

Referring to the drawings, the numeral 1 designates a conventional form of gin and 2 the sides thereof. The gin casing comprises sections 3 and 4 which are hingedly connected together as at 5 thereby allowing access to the interior of the gin when the hinged section 4 is moved outwardly and upwardly at its lower end. Rotatably mounted in the gin casing 1 is a drum comprising a plurality of gin saws 6, which saws as they revolve gather the fiber, pass the same around and between the gin ribs 7, said gin ribs being spaced apart a sufficient distance to allow the cotton to pass through the same but not sufficiently far apart to allow the passage of the cotton seed, thereby separating the cotton fiber from the seed.

It has been found that as the saws 6 revolve that they become gummed and clogged, that is gummed from the cotton seed and clogged with cotton fiber. When this occurs it is necessary for the operator to clean the saws manually while they are revolving which operation is a slow and dangerous one. To overcome this difficulty and to quickly clean the saws the cleaner bar 8 is provided which extends transversely of the gin and has its ends provided with rectangular shaped portions 9 which are slidably mounted in arcuate slots 10 in the sides of the pivoted section 4 of the gin frame. Extending upwardly from the upper face of the cleaner bar 8 are cleaning fingers 11, which fingers clean the saw teeth as they revolve, thereby obviating the manual cleaning of the saw teeth as is now the practice. Extending outwardly from the rectangular shaped portions 9 are the reduced cylindrical portions 12, which cylindrical portions are disposed in the bifurcations 13 of segmentally shaped levers 14.

The levers 14 are pivoted at their central points 15 to the section 3 of the gin frame and are adapted to be rocked on said pivotal point when the section 4 moves outwardly at its lower end. The rocking of the levers 14, when the lower end of the casing section 4 is moved outwardly is caused by the connecting rods 16, one end of said

rods is connected pivotally as at 17 to each lever 14, while the other ends of said rods 16 are connected pivotally as at 18 to the sides of the casing section 4.

5 The operation is as follows. When the saws become clogged the lower end of the casing 4 is moved outwardly, thereby causing a downward rocking of the end 14^a of the lever 14. This action will cause the bifurcated end of the lever 14 to move upwardly, thereby causing the cleaner bar 8 to be forced upwardly in its guide slot 10, thereby forcing the fingers 11 of the cleaner bar into position whereby the teeth of the 10 saws will be cleaned as they revolve. During this operation it will be seen that it has not been necessary for the operator to place his hands in any position where they may be injured by the revolving saws. It will also 15 be seen that enough fingers are provided for cleaning all of the saws in one operation, thereby reducing the time for a saw cleaning operation to a minimum.

It is obvious that in some types of gins 20 the bar 8 may be forced upwardly into operative position by a foot operated lever instead of through the connecting rod 16.

From the above it will be seen that a gin saw cleaning device is provided which is 25 simple in construction and one wherein the 30

device may be applied to various types of gins without materially changing their structures.

The invention having been set forth what is claimed as new and useful is:—

The combination with a gin having rotatable saws therein, of a saw cleaning device therefor, said saw cleaning device comprising a bar extending transversely of the gin and disposed beneath the saws, upwardly 40 extending fingers carried by the bar, the ends of said cleaner bar being rectangular shaped and slidably mounted in segmentally shaped upwardly extending slots in the sides of the gin, a lever pivoted to the sides of the 45 gin at a point centrally of the lever, one end of said lever being provided with a bifurcation in which the ends of the cleaner bar are disposed and means for rocking said lever for forcing the cleaner bar upwardly 50 and the cleaner fingers into a position for cleaning the teeth of the saws.

In testimony whereof I have signed my name to this specification in the presence of two subscribing witnesses.

LESLIE SYDNEY POPE.
